[57] ABSTRACT

An opened-ended, four-sided structure for slidably retaining the tool therewithin, with a pilot dowel pin fixed to an end of the structure and extending therefrom into the structure. The pin is slidably received by a cylinder. The cylinder has pressured fluid inlet and vent ports in the wall thereof, and an external terminal end of the cylinder abuts a surface of the tool. The pin cooperates with an annular sleeve disposed about a portion of the inner cylinder wall to seal off the vent port until the cylinder, under pressured-fluid force, travels a predetermined distance to effect a tool movement stroke. Toward the end of the stroke, the vent port is uncovered and evacuates fluid from the cylinder.

TOOL FIXTURE

This invention pertains to a fixture for supporting a fluid-powered tool for the address thereof to a work-face, and in particular to such a tool supporting fixture which is fluid-powered for moving the tool a predetermined distance with means automatically operative for venting the enabling fluid, when the tool has been moved said predetermined distance, to halt both tool movement and operation.

In the prior art it is known for fixtures to support tools and advance them under the influence of fluid power. However, known devices of this type have to be manually controlled, either to effect the movement of the tool, to vent the fluid which operates the fixture, or both.

It is an object of this invention to teach a fluid-powered tool-moving fixture having means for supporting the tool; means for engaging a surface of said tool for moving the tool in a given direction, having a fluid-pressure bearing surface and being movable in said given direction in response to a fluid pressuring of said bearing surface; and means coupling said surface-engaging means and said tool-supporting means together, wherein said coupling means comprises means which pilot the movement of said engaging means along said given direction; said engaging means has port means for admitting pressured fluid to said bearing surface and for venting fluid therefrom; and said pilot means and said engaging means cooperate to prevent venting of fluid from said bearing surface until said engaging means has traveled a predetermined distance in said direction and cooperatively and automatically vent fluid from said bearing surface, via said port means, when said engaging means has traveled said predetermined distance.

A feature of this invention comprises an open-ended, four-sided structure for slidably retaining a tool therewithin with a dowel-pin fixed to an end of the structure and extending therefrom into the structure. The dowel-pin slidably receives a cylinder which cylinder has fluid inlet and vent ports in the wall thereof and one end of the cylinder abuts a surface of the tool to effect tool movement. The dowel-pin cooperates with an annular sleeve replaceably disposed in a given position about a portion of the inner cylinder wall to seal off the vent port until the piston has traveled a predetermined distance.

Further objects and features of this invention will become more apparent by reference to the following description taken in conjunction with the accompanying figures in which:

FIG. 1 is a top view of the fixture according to the invention showing a tool disposed therewithin;

FIG. 2 is a side elevation of the fixture and tool of FIG. 1, with a portion cut away showing, in vertical cross-section, the dowel-pin and cylinder as associated at the start of an operational stroke; and

FIG. 3 is a front elevational view, partly in cross section, taken along section 3-3 of FIG. 1, showing the dowel-pin and cylinder relationship at the end of an operational stroke;

FIG. 4 is a view like that of FIG. 3 showing fluid supply and vent ports for a tool operating means through communicating with the cylinder supply and vent ports;

FIG. 5 is a schematic representation of the fixture and tool arrangement of FIG. 4; and

FIG. 6 is a schematic representation of an alternate fixture and tool arrangement according to the invention.

As shown in FIG. 1 and 2 the fixture 10 comprises means for supporting a tool for movement, and includes a structure 12 having side walls 14 and 14', rear wall elements 16, and front wall elements 18. The tool 20, here shown only in part, is a fluid-powered impact ram.

The tool 20, the impact ram only partly shown, is substantially identical to the impact ram automatically and cyclically operated in accordance with the teachings of my co-pending patent application Ser. No. 695,194, for "Control Means for Fluid-powered Devices," filed Jan. 2, 1968. The only difference of significance, between tool 20 and that disclosed in the afore-mentioned pending application is that in tool 20 the end cap presents two pair of fluid intake and discharge ports, and the pertinence thereof to this invention is explained in the ensuing text.

The tool 20 is slidably restrained within the fixture 10 by means of slide bearings 22 carried by the fixture internally of the walls 14 and 14', and elements 16 and 18. A cylinder 24 disposed within a raised pocket 26 formed in side wall 14 receives a dowel-pin 28. Dowel pin 28 depends from a horizontal web 30 arranged across the top of pocket 26 and slidably receives cylinder 24 thereon pin 28 comprises means for coupling together the tool moving cylinder 24 and the tool-supporting structure 12. A lower closed end 32 of cylinder 24 abuts a surface 34 of the tool, the surface being presented by a horizontal rib 36 on the tool casing.

As shown in FIG. 3, cylinder 24 has a fluid inlet port 38 and a fluid outlet port 40 formed the wall thereof, said ports being exposed to communicate with a chamber 42. The chamber 42 is formed by a fluid bearing surface 44 which defines the inner bounds of a cavity 46 formed in cylinder 24, the surface 44 being spaced from dowel-pin 28.

As the dowel-pin 28 is fixed to the structure 12, pressurization of surface 44 causes the cylinder 24 to move relative to the dowel-pin 28. Such pressurization is effected by communication of port 38 with a pressured fluid top off port 48 of the tool 20 which is aligned therewith. However, at the start of the stroke (FIG. 2) port 40 is sealed off by dowel-pin 28 and a sleeve 50 disposed between the dowel-pin and the surface 44. Until cylinder 24 has traveled so far as to move sleeve 50 beyond port 40, the cavity 46 cannot be vented. When port 40 is uncovered by sleeve 50 the movement of the tool 20 by cylinder 24 is terminated; the pressured fluid is vented through a communication of port 40 with a fluid exhaust port 52 of the tool which is aligned therewith. Thereafter the fluid supply to the cylinder (and to the tool 20) is cut off (by control means not shown) and the tool 20 can be slid back into a start position in the structure 12.

Sleeve 50 is replaceably retained in cylinder 24 by means of a retaining ring 54, and the abutting of the inner end thereof against a shoulder 56 formed in cylinder 24.

Cylinder 24 is constrained against the tool 20 by the fastening of walls 14 and 14' to the sides of the tool by assembly bolts 58 and nuts 60. Thus, the enclosure of the cylinder within the pocket 26, and within the structure as a whole, cooperates with dowel pin 28 to guide movement of the cylinder relative to the structure. O-ring seals arranged in a tool-facing surface of cylinder 24 seal the ports 38 and 40 to the provisioned pressured-fluid supply and venting means, respectively. These latter are shown to be the fluid tap-off port 48 and the fluid exhaust port 52 of tool 20.

Tool 20 can be any fluid-powered tool having first fluid intake and discharge ports 62 and 64, respectively, as shown in FIG. 3, for enabling a pressured fluid operation of the tool, which ports 62 and 64 communicate (by means not shown here) with ports 48 and 52, respectively. Accordingly, as the tool 20 is moved relative to the fixture 10 to the position shown in FIG. 3, such positioning will halt the operation of the tool. Tool operation halts in that the enabling supply of fluid is vented through cavity 46, ports 40 and 52, and finally port 64. Of course, until port 40 is uncovered, tool operation, and tool movement within fixture 10, occur simultaneously; they cease simultaneously also.

My novel fixture 10 is especially suitable for use with fluid-powered tools such as the impact ram described in the afore-mentioned patent application Ser. No. 695,194, and more so with such a ram being deployed in a paving breaker usage. Thus, I show my fixture walls 14 and 14' as comprising a pair of gussets 66 with bore holes 68 therein for mounting of my fixture 10 to an ancillary machine--such as backhoe, for instance.

Finally, for purposes of illustration, tool ports 62 and 64 are shown as being coupled to lines or hoses 70 and 70'. In that the tool 20 carries the ports 62 and 64 and any such coupled hoses 70 and 70' therewith, as it slides on bearings 22, the fixture 10 has a raised pocket 26' in side wall 14' with a relief or slot 72 therein to accommodate the travel of hoses 70 and 70' therealong.

FIGS. 4 and 5 more clearly illustrate the use of the fixture 10 for controlling tool movement and tool operation as well. With reference to FIG. 4, it will be seen that a "tool operating means" 74 is confined within tool 20, and such means contemplate that disclosed in my co-pending application Ser. No. 695,194, or equivalent means. Accordingly, means 74 is responsive to pressured fluid, supplied via intake port 62, to operate the tool 20. Discharge port 64 discharges fluid from means 74. As FIGS. 4 and 5 show, the fluid supply provided via port 62 is communicated with the cylinder 24 through means 74 and ports 38 and 48. Ports 40 and 52 are also in communication with port 64 through means 74. As long as port 40 is sealed off, means 74 will operate the tool 20. When port 40 is uncovered, the pressured fluid supply at port 62 is effectively shunted through the novel fixture 10 and its cylinder 24, and tool operation halts.

While I have described my invention in connection with a specific embodiment thereof it is to be clearly understood that this is done only by way of example and not as a limitation to the scope of my invention as seen in the objects thereof and in the accompanying claims. For instance, it is not at all necessary, as FIG. 6 illustrates, that the fixture enabling fluid be communicated through the tool itself. It is sufficient, to prac-

tice my invention, to fluid-couple my novel fixture, and the cylinder 24 thereof, with single inlet and vent ports 62 and 64, respectively, of a given tool. This arrangement, shown schematically in FIG. 6, provides a parallel operation of the fixture with the tool—as long as port 40 is sealed off, and a serial arrangement, through which the tool-enabling fluid is shunted via the fixture, which halts both movement of the tool by the fixture and operation of the tool simultaneously.

I claim:

1. A fluid-powered fixture for supporting a tool for movement, comprising:
means for slidably supporting the tool;
means for abuttingly engaging a surface of said tool, for slidably moving said tool relative to said supporting means, having a fluid-pressure bearing surface, and being movable in response to a fluid pressuring of said bearing surface; and
means coupling said surface-engaging means and said tool-supporting means together; wherein
said coupling means comprises guide means which, cooperative with said supporting means, guides the movement of said engaging means;
said engaging means has port means for admitting pressured fluid to said bearing surface and for venting fluid therefrom; and
said guide means and said engaging means cooperate to prevent venting of fluid from said bearing surface until said engaging means has traveled a predetermined distance, and cooperatively and automatically vent fluid from said bearing surface, via said port means, when said engaging means has traveled said predetermined distance.

2. A fixture, according to claim 1, wherein:
said engaging means comprises a cylinder, having an external surface disposed for effecting said abutting engagement with said tool surface, and an elongated, walled cavity formed therein and enclosed at one end only;
said port means comprising an inlet port and a vent port formed through the wall of said cavity;
said guide means comprises a dowel-pin fixed at one end thereof to said tool supporting means and projecting therefrom into said cavity;
said cylinder further having sealing means disposed within said cavity cooperative with said dowel pin to close off said vent port.

3. A fluid-powered fixture for supporting a tool for movement, comprising:
means for slidably supporting the tool;
means for engaging a surface of said tool, for slidably moving said tool relative to said supporting means, having a fluid-pressure bearing surface, and being movable in response to a fluid pressuring of said bearing surface; and
means coupling said surface-engaging means and said tool-supporting means together; wherein
said coupling means comprises guide means which, cooperative with said supporting means, guides the movement of said engaging means;
said engaging means has port means for admitting pressured fluid to said bearing surface and for venting fluid therefrom; and
said guide means and said engaging means cooperate to prevent venting of fluid from said bearing sur-

face until said engaging means has traveled a predetermined distance, and cooperatively and automatically vent fluid from said bearing surface, via said port means, when said engaging means has traveled said predetermined distance; wherein said engaging means comprises a cylinder, having an external surface disposed for abutting engagement with said tool surface, and an elongated, walled cavity formed therein and closed at one end only; said port means comprises an inlet port and a vent

10

port formed through the wall of said cavity; said guide means comprises a dowel-pin fixed at one end thereof to said tool supporting means and projecting therefrom into said cavity;

15

said cylinder further has sealing means disposed within said cavity cooperative with said dowel pin to close off said vent port; and

20

said sealing means comprises a sleeve interposed between said dowel-pin and said cavity wall.

4. A fixture, according to claim 3, wherein:

said supporting means comprises an open-ended, quadrilateral structure having means for slidably retaining said tool therewithin.

5. A fixture, according to claim 4, wherein:

said retaining means comprises slide-bearing-surfaced elements carried on internal surfaces of said structure.

6. A fixture, according to claim 3, further including:

a replaceable retaining ring, carried by said piston, 30 holding said sleeve in position.

7. A fixture, according to claim 3, wherein:

said sleeve has a bore-hole formed through a side thereof, said bore-hole being in throughgoing, communicating alignment with said vent port.

35

8. A fixture, according to claim 5, wherein:

said structure has a pair of gussets extending in parallel therefrom to facilitate a coupling of said structure to an ancillary machine or device.

9. In combination with a tool having pressured-fluid discharging and intake ports, a fluid-powered fixture for supporting and automatically moving the tool, comprising:

an open-ended structure for slidably supporting the tool;

45

means for engaging a surface of said tool, for slidably moving said tool relative to said structure, having a fluid-pressure bearing surface, and being movable in response to a fluid pressuring of said bearing surface; and

50

means coupling said surface-engaging means and said structure together; wherein

said coupling means comprises guide means which, cooperative with said structure, guides the movement of said engaging means;

said engaging means includes means for admitting pressured fluid to said bearing surface, and means for venting fluid therefrom, said fluid admitting means being in throughgoing communication with said intake port, and said fluid venting means being in throughgoing communication with said discharging port; and

60

said guide means and said engaging means cooperate to prevent venting of fluid from said bearing surface until said engaging means has traveled a predetermined distance, and cooperatively and au-

tomatically vent fluid from said bearing surface, via said fluid venting means, when said engaging means has traveled said predetermined distance.

10. A fixture, according to claim 9, wherein:

said engaging means comprises a cylinder having an external surface disposed for abutting engagement with said tool surface, and an elongated, walled cavity formed therein and closed at one end only; said admitting means and said venting means comprise an inlet port and a vent port, respectively, formed through the wall of said cavity;

said guide means comprises a dowel-pin fixed at one end thereof to said structure and projecting therefrom into said cavity;

said cylinder further having sealing means disposed within said cavity cooperative with said dowel-pin to close off said vent port.

11. A fixture according to claim 10, wherein:

said sealing means comprises a sleeve interposed between said dowel-pin and said cavity wall.

12. A fixture, according to claim 11, further including:

a replaceable retaining ring, carried by said cylinder, holding said sleeve in position.

13. A fixture, according to claim 11, wherein:

said sleeve has a bore-hole formed through a side thereof, said bore-hole being in throughgoing, communicating alignment with said vent port.

14. A fixture, according to claim 9, wherein:

said structure comprises slide-bearing-surfaced elements carried on internal surfaces thereof for slidably retaining said tool therebetween.

15. A fixture, according to claim 14, wherein:

said structure has a pair of gussets extending in parallel therefrom to facilitate a coupling of said structure to an ancillary machine or device.

16. In combination with a fluid-powered tool having first means supplying pressured fluid thereto for enabling tool operation and second means for venting fluid therefrom, a fluid-powered fixture for moving the tool and for controlling tool operation, comprising:

means for engaging a surface of said tool;

said engaging means having a bearing surface responsive to a fluid pressuring thereof to cause movement of said engaging means and, as a result, to effect movement of said tool;

means interconnecting said first means with said bearing surface and providing a first fluid communication therebetween;

means effective for interconnecting said second means with said bearing surface for providing a second fluid communication therebetween; and

guide means fixed against movement, relative to said engaging means, for guiding movement of said engaging means and effective, in a first fixed position, relative to and coincident with movement of said engaging means, for interdicting said second fluid communication, and effective in a second fixed position relative to said engaging means upon movement of the latter, for automatically accommodating said second fluid communication, said guide means guiding movement of said engaging means and enabling an operation of said tool when said guide means is in said first relative position, and halting said movement and operation when said guide means is in said second relative position.

17. A fixture, according to claim 16, wherein:
said engaging means further includes means for sup-
porting said tool.
